Des. 656

Apollos Richmond of Providence, R.I.

Assignor to

A.C. Barstow, & Co. of same place.

Letters Patent No. 656. Dated June 13th, 1854.

The schedule referred to in these Letters Patent, and making part of the same.

To all persons to whom these presents shall come:

Be it known that I, Apollos Richmond, of Providence, in the County of Providence, and State of Rhode Island, have produced a new and original design for a cooking stove, and I hereby declare that the said new design is fully described and represented in the following specification and accompanying drawings to which reference is hereinafter made.

The figures of the accompanying plate of drawings represent my new design.

In Plate 1, Fig. 1, is an elevation of the front plate of the stove, and Fig. 2, a section of the same, taken in the plane of the line A,B, Fig. 1, showing the form of the mouldings.

In Plate 2, Fig. 3, is an elevation of one of the side plates.

And Fig. 4, a section of the same taken in the plane of the line

C,D. Fig. 3.

The top or upper portion of the front plate, Fig. 1, Pl. 1, has on it the words "Lilly Dale", in raised letters, and under the said words a music staff a.a. Under the staff, is the following quotation from the song of "Lilly Dale":-

"There was a calm still night,
And the moon's pale light,
Shone soft o'er hill and vale,"

in raised letters. The doors of the front plate have a raised figure b.b, in the center of each and around them, the mouldings c.c, and small diamond shaped figures, d.d.

The side plate, Fig. 3, Plate 2, has across the top, the ornamental fringe work e.e, and raised circular drops ff, &c,

The oven door has around it the mouldings c.c. and diamond figures d.d, and in its center the large raised figure g.g, surrounded with the curved fringe work e.e. The panel h has around it the mouldings c.c, and diamond figures d.d, and is ornamented in the center, with the raised figure k.

The bottom of the plate has on it the raised semi circles l.l, &c, and drops m.m.

Having thus described my new design, I shall state my claim as follows:

What I claim as my invention, and desire to have secured to me by Letters Patent is, the new design consisting of the music staff, raised figures, and ornamental configurations, as herein above described and represented in the drawings for the side and front plates of a cooking stove.
